US00D684483S

(12) **United States Design Patent**
Jahina et al.

(10) **Patent No.:** **US D684,483 S**
(45) **Date of Patent:** **** Jun. 18, 2013**

(54) **CONTAINER**

(75) Inventors: **Adrian Jahina**, Olney (GB); **Jon Winter**, Cranfield (GB)

(73) Assignee: **Rexam Beverage Can Europe Limited**, Luton (GB)

(**) Term: **14 Years**

(21) Appl. No.: **29/381,382**

(22) Filed: **Dec. 17, 2010**

(30) **Foreign Application Priority Data**

Jun. 17, 2010 (EM) 001721192-0001

(51) **LOC (9) Cl.** **09-01**

(52) **U.S. Cl.** **D9/772**
USPC .....

(58) **Field of Classification Search**
USPC D9/500, 516, 549, 574, 763-783;
215/381-385; 220/660, 662, 669

See application file for complete search history.

(57) **CLAIM**

We claim the ornamental design for a container, as shown and described, the bottom of which is plain and unadorned.

DESCRIPTION

FIG. 1 is a perspective view of the present invention;
FIG. 2 is a top view of the present invention;
FIG. 3 is a side view of the present invention; and,
FIG. 4 is a bottom view of the present invention.
Features shown in broken lines in the drawings are not part of the claim.

1 Claim, 4 Drawing Sheets
